INTERLOCKING CONTROL APPARATUS

Charles W. Bell, Wilkinsburg, Pa., assignor to
The Union Switch & Signal Company, Swiss-
vale, Pa., a corporation of Pennsylvania

Application March 19, 1935, Serial No. 11,807

35 Claims. (Cl. 246—161)

My invention relates to interlocking control apparatus, and is particularly adapted for, though not limited to, apparatus for controlling railway track switches and signals in a railway switching or interlocking layout.

One feature of my invention is the provision of novel and improved group releasing means for a plurality of devices such, for example, as signal lever locks or locking relays for a plurality of railway track switches.

I will describe four forms of apparatus embodying my invention, and will then point out the novel features thereof in claims.

In the accompanying drawings, Figs. 1 and 2 are diagrammatic views showing one form of apparatus embodying my invention. Fig. 2^a is a diagrammatic view showing a modification of the arrangement of Fig. 2. Figs. 3, 4, 5, 6 and 7 are diagrammatic views showing a third form of apparatus, also embodying my invention. A fourth form of apparatus embodying my invention comprises a combination of the parts shown in Figs. 2^a, 3, 4, 5 and 6.

Similar reference characters refer to similar parts in each of the views.

Referring first to Fig. 1, railway tracks designated by the reference characters X, Y and Z, respectively, are shown interconnected by switches W¹, W^{1a} and W². The reference characters 1 and 1^a designate the rails of track Z, and the reference characters 2 and 2^a designate the rails of track Y.

These rails are divided by insulated joints 3 to form a plurality of track sections a—b, b—c, d—e, and e—f. Each track section in which a switch is located will be referred to hereinafter as a detector section. Track sections a—b and e—f in the rear of signals S¹ and S⁴, respectively, will be referred to as approach track sections.

Each of the track sections is supplied with current by a battery 4 connected across the rails adjacent one end of the section. A track relay, designated by the reference character T with a distinguishing exponent, is connected across the rails adjacent the opposite end of each track section.

Reference character S with distinguishing exponents designates signals which are placed adjacent points b, c, d and e, and which, as here shown, are of the semaphore type, but which may be of any other suitable type. Signals S^{1a} and S^{1b} are mounted on a common mast 5, and signals S^{4a} and S^{4b} are mounted on a common mast 6. Signals S^{1a}, S^{1b} and S² govern eastbound traffic movements, that is, movements which are

made over the stretch of tracks from left to right as shown in the drawings, and signals S³, S^{4a}, S^{4b} and S⁵ govern westbound traffic movements, that is, movements which are made over the stretch of tracks from right to left as shown in the drawings.

Each switch W is operated by a mechanism which may be an electric motor or any other suitable device, designated by the reference character w with an exponent corresponding with that of the reference character W for the switch. Mechanism w² for operating switch W² is shown controlled by pole-changing contacts 7 and 8 of a manually operable switch lever VW², and also by a normally closed contact 9 of switch W¹, and by normally closed contacts 10^{V1-5}, 11^{V2-4} and 12^{V3} of manually operable signal levers V¹⁻⁵, V²⁻⁴ and V³, respectively. Mechanism w¹ is controlled by pole-changing contacts 7 and 8 of manually operable switch lever VW¹, and by normally closed contacts 13, 14 and 15 of levers V¹⁻⁵, V²⁻⁴, and V³, respectively. Mechanism w^{1a} may be controlled similarly to mechanisms w¹ and w², or it may be controlled in multiple with mechanism w¹.

The switch and signal levers V may be mechanically interlocked. If they are mechanically interlocked, the normally closed contacts of the signal levers can be omitted from the control circuits for the switch operating mechanisms w.

Each of the switch levers VW¹ and VW² has a normal position n and a reverse position r. The pole-changing contacts 7 and 8 of each of these levers close a normally energized circuit for the associated mechanism w when the corresponding lever V is in its n position, and close a reverse energizing circuit for the associated mechanism w when the corresponding lever V is in the r position.

Each of the signal levers V¹⁻⁵, V²⁻⁴ and V³ has a normal position N, a reverse position L to the left as shown in the drawings, a normal lock or indication position B to the left, a reverse position R to the right, and a normal lock or indication position D to the right. Lever V¹⁻⁵ operates seven contacts, namely, contact 10^{V1-5} in the circuits for mechanism w², contacts 13, 47, 54 and 56 shown adjacent the representation of lever V¹⁻⁵, and contacts 64^{V1-5} and 65^{V1-5} in the circuits for time element relay TE of Fig. 2. Lever V²⁻⁴ operates seven contacts, namely, contact 11^{V2-4} in the circuits for mechanism w², contacts 14, 31, 38 and 42 shown adjacent the representation of lever V²⁻⁴, and contacts 64^{V2-4} and 65^{V2-4} in the circuits for time element relay TE of Fig. 2.

Lever V^3 operates five contacts, namely, contact $12V^3$ in the circuits for mechanism w^2 , contacts 15 , 17 and 20 shown adjacent the representation of lever V^3 , and contact $64V^3$ in the circuit for time element relay TE of Fig. 2.

Adjacent the symbol for each of the contacts of signal levers V a reference character is placed to designate the position or positions of the associated lever at which each of these contacts is closed. For example, the letter N adjacent contact 15 of lever V^3 means that contact 15 is closed when lever V^3 is in its N position only; letter L adjacent contact 17 of lever V^3 means that contact 17 is closed only when the lever is in its reverse position L ; the letter B adjacent contact 20 of lever V^3 means that contact 20 is closed only when lever V^3 is in the B position; letter L to the left and letter R to the right of contact 31 of lever V^{2-4} mean that contact 31 is closed only when lever V^{2-4} is in its L position or its R position; and letters LB placed together adjacent contact 42 of lever V^{2-4} mean that contact 42 is closed when lever V^{2-4} is in either its L or its B position or at any point between these two positions.

Each signal lever V can be returned to its N position from either its L or its R position only when an associated electric lock is energized. Each of these electric locks is designated by the reference character K with an exponent corresponding to that of its lever. Each electric lock K comprises a control winding 27 , a segment 30 , and a locking dog 28 which is controlled by winding 27 . Segment 30 is provided with a lug 29 . Each segment 30 is mechanically connected with its lever V , as indicated in the drawings by the dash lines. One manner of connecting each segment 30 with its lever V is such that when the associated lever V is moved to the left, the segment 30 will be moved to the right, or if the lever V is moved to the right, the segment 30 will be moved to the left. If, when any one of the signal levers V is moved to either of its reverse positions L and R , the winding 27 of the associated electric lock K becomes deenergized, the dog 28 controlled by that winding 27 will rest on its segment 30 , and if then an attempt is made to return the lever to its N position, dog 28 will engage lug 29 when the lever reaches its position B or D , and will thus prevent complete return of the lever to its N position until the associated winding 27 is again energized.

Each signal lever S is controlled by a signal relay which is designated by the reference character H with an exponent which corresponds with the exponent of its signal. Each relay H is controlled by one of the signal levers V in one of its reverse positions, and by other conditions such, for example, as the positions of the switches in the route over which traffic is governed by the corresponding signal. For example, a route relay A^3 which controls relay H^3 in part is shown controlled by a circuit which is controlled in part by switch W^2 , and which is closed only when switch W^2 is in its reverse position. Relay A^3 may also be controlled by switches W^1 and W^{1a} . Each of the other relays A may be similarly energized only when each switch in an associated route is in the position required for that route. Each of the relays H is controlled by a corresponding route relay A , and hence each relay H is energized only when the switches of a corresponding route are in the position required for the route.

Winding 27 of each electric lock K is energizable under given traffic conditions only when its

lever is in one of its lock or indication positions B and D .

A selector relay, or release stick relay E is provided for each signal lever V , and one time element relay TE , shown in Fig. 2, is provided for all the signal levers V . By means of time element relay TE and each stick relay E , an associated electric lock K can be energized upon the lapse of a measured period of time after an associated relay H is deenergized by movement of an associated signal lever V to one of its lock positions B and D . Relay TE is so constructed that, upon becoming energized, a measured interval of time must elapse before its front contacts will close, but upon becoming deenergized, its back contacts will quickly close.

Time element relay TE is energizable under given traffic conditions only when one of the levers V is in its reverse lock position B or D . When relay TE is energized, it may at any time be deenergized if one of the manually operable push button circuit controllers v is opened. A push button circuit controller v may be provided for each signal lever V , as shown in the drawings, and may be distinguished by an exponent corresponding to that of the associated lever V .

A repeater relay, designated by the reference character P , is shown energized in Fig. 2, whenever relay TE is in its deenergized condition. An indicator, here shown as an electric lamp i , is controlled by a front contact of relay P .

In each of the drawings, the contacts operated by the various relays or by the levers V are identified by numbers, such numbers having distinguishing exponents when the contacts are shown elsewhere than adjacent the representation of the relay or lever by which they are operated. The exponent for each of these contact numbers comprises the reference character and exponent for the respective relay or lever. For example, the exponent $T3$ for contact $21T^3$ in the pick-up circuit for winding 27 of lock K^3 in Fig. 1 comprises the reference character T and its exponent 3 for track relay T^3 which operates contact $21T^3$. Similarly, the exponent V^3 for contact $64V^3$ in one of the circuits shown for relay TE in Fig. 2 comprises the reference character V and its exponent 3 for signal lever V^3 which operates contact $64V^3$.

Fig. 2a is the same as Fig. 2 except that relay TE is here controlled by only the push button circuit controllers v , and is therefore normally energized, whereas in Fig. 2 it is normally deenergized. With relay TE controlled as shown in Fig. 2a, relay P and indicator i are normally deenergized, whereas with relay TE normally deenergized as shown in Fig. 2, relay P and indicator i are normally energized.

In the first and second forms of apparatus embodying my invention, the signal levers V are electrically locked by locks K as shown in Fig. 1, and may also be mechanically interlocked with the switch levers V . However, in the third and fourth forms of apparatus embodying my invention, the switch and signal levers V are not interlocked nor otherwise locked, but are free to be moved at any time.

In the third and fourth forms of apparatus embodying my invention, approach locking relays M^1 and M^4 , and stick locking relays M^2 , M^3 and M^5 , shown in Fig. 6, are used instead of the signal lever locks K shown in Fig. 1; the slow release relays F , one for each relay M , are used instead of relays E shown in Fig. 1; the switch mechanisms w are controlled, in part, by front contacts of

relays M, as shown in Fig. 3, instead of by normally closed contacts of the signal levers; and the track and signal layout is as shown in Fig. 1, but the control of the switches and signals is modified as shown in Figs. 3, 4 and 5.

In Fig. 4, signal relays H are shown controlled by non-locked levers, and in Fig. 5, auxiliary signal relays h are shown controlled by relays H. Circuits are shown in Fig. 5 for only relays h^{1a} , h^{1b} , h^2 and h^5 . The circuits for relays h^3 , h^{4a} and h^{4b} are similar to those shown for relays h^2 , h^{1a} , h^{1b} and are, therefore, omitted from the drawings.

Time element relay TE is shown normally energized, in Fig. 7, through front contacts of locking relays M.

Having described, in general, the arrangement of various forms of apparatus embodying my invention, I will now trace in detail the operation 20 of these forms of apparatus.

As shown in the drawings, all parts are in the normal condition, that is, each track relay T is energized; each switch and signal lever V, and each push button circuit controller contact v is 25 in its normal position; each switch W is in the normal position; each signal S is indicating stop; some of the route relays A are energized, and others are deenergized; relay P and indicator i are energized in Fig. 2, but are deenergized in 30 Figs. 2a and 7; relay TE is energized in Figs. 2a and 7, but is deenergized in Fig. 2; relays M and switch mechanisms w are energized; and lock magnets 27 and relays E, H, h and F are deenergized.

35 I will first trace the operation of the first form of apparatus, shown in Figs. 1 and 2.

With the switch and signal levers V in their normal positions, normal control circuits are closed for switch mechanisms w. The circuit for 40 mechanism w^1 passes from terminal x of a suitable source of current not shown in the drawings, through contact 7 of lever VW¹ in its n position, contacts 13, 14 and 15 of levers V¹⁻⁵, V²⁻⁴ and V³, respectively, in their N positions, mechanism w^1 , 45 and contact 8 of lever VW¹ in its n position to terminal o of the same source of current. A similar circuit is closed for mechanism w^2 , passing from terminal x, through contact 7 of lever VW² in its n position, contacts 10^{V1-5}, 11^{V2-4} and 50 12^{V3}, mechanism w^2 and contact 8 of lever VW² back to terminal o. A branch path for this circuit is also closed through contact 9 which is operated in conjunction with mechanism w^1 , and which is closed only when switch W¹ is in the 55 normal position.

With relay TE deenergized, a circuit is closed for relay P including back contact 68 of relay TE. With relay P thus energized, indicator i is energized by a circuit which includes front 60 contact 69 of relay P.

I will assume that the leverman, in order to clear signal S^{1a}, moves lever V¹⁻⁵ to its R position, thereby completing a circuit for relay H^{1a}, passing from terminal x, through contact 47 of lever V¹⁻⁵ in the R position, contact 48 of route relay A^{1a}, and the winding of relay H^{1a} to terminal o. Relay H^{1a}, upon becoming energized, completes a circuit for signal S^{1a}, passing from terminal x, through contact 63^{H1a}, and the mechanism of signal S^{1a} to terminal o, thereby causing the arm of signal S^{1a} to be operated to the proceed position.

If the leverman should decide to return signal S^{1a} to its stop position before a train arrives on approach section a—b, he will return lever V¹⁻⁵ to its D position, thereby completing an energizing

circuit for lock K¹⁻⁵, passing from terminal x, through contacts 51, 52 and 53 of relays H^{1a}, H^{1b} and H⁵, respectively, contact 54 of lever V¹⁻⁵ in the D position, contact 55^{T1}, contact 56 of lever V¹⁻⁵ in the D position, and winding 27 of lock K¹⁻⁵ to terminal o. Winding 27, upon becoming energized, closes its contact 57, thereby completing its own stick circuit which is the same as the pick-up circuit previously traced except that it includes contact 57 instead of contacts 55^{T1} and 56. Winding 27 will therefore be retained in the energized condition, irrespective of the condition of track relay T¹, as long as lever V¹⁻⁵ is left in the D position. Winding 27 of lock K¹⁻⁵, upon becoming energized, also removes dog 28 from 10 engagement with lug 29 of segment 30 of lever V¹⁻⁵, and hence the leverman can complete the return of lever V¹⁻⁵ to its N position. Lever V¹⁻⁵, when moved to its D position as just described, closes its contact 65^{V1-5} in one of the circuits for 15 relay TE, but contact 66^{T1} is open if no train is in section a—b, and hence relay TE does not become energized.

I will assume that after lever V¹⁻⁵ is returned to its position N, the leverman again desires to 20 clear signal S^{1a}, and therefore again moves lever V¹⁻⁵ to its R position. I will also assume that an eastbound train arrives in section a—b, and then closes its contact 65^{V1-5} in one of the circuits for 25 relay TE, but contact 66^{T1} is open if no train is in section a—b, and hence relay TE does not become energized.

If now the leverman returns lever V¹⁻⁵ to the reverse lock position D, a second pick-up circuit will be closed for winding 27 of lock K¹⁻⁵, which is the same as the first pick-up circuit as far as contact 54 of lever V¹⁻⁵, and thence passes 30 through contact 58^{T2}, and winding 27 of lock K¹⁻⁵ to terminal o. Lever V¹⁻⁵ can now be returned to its N position irrespective of whether contact 55^{T1} in the first pick-up circuit is open on account of part of the train reaching back into section a—b, or on account of a second train having 35 entered section a—b.

I will next assume that after lever V¹⁻⁵ has been returned to its N position, the leverman again 40 clears signal S^{1a} by moving lever V¹⁻⁵ to its R position, and that after a train enters approach section a—b, but before it has reached signal S^{1a}, the leverman returns signal S^{1a} to the stop position by moving lever V¹⁻⁵ away from the R position. When lever V¹⁻⁵ reaches the D position, the 45 pick-up circuit first traced for winding 27 of lock K¹⁻⁵ will be open at contact 55^{T1} on account of relay T¹ being deenergized due to the presence of the train in section a—b, and the second pick-up circuit previously traced will be open at contact 55^{T2} on account of detector section b—c being unoccupied. Lever V¹⁻⁵ will therefore be held in its D position by engagement of its dog 28 with lug 29 of its segment 30.

A circuit will now be completed for time element relay TE, passing from terminal x, through contacts 65^{V1-5}, 66^{T1}, 67^{T2}, v³, v²⁻⁴, and v¹⁻⁵, and the winding of relay TE to terminal o. At the same time that this circuit for relay TE is completed, a circuit is also completed for release 60 relay E¹⁻⁵, which is the same as the first pick-up circuit for lock K¹⁻⁵ as far as contact 54 of lever V¹⁻⁵, and thence passes through contact 59^P, and the winding of relay E¹⁻⁵ to terminal o. Relay E¹⁻⁵, upon becoming energized, completes its 65 stick circuit which is the same as the pick-up circuit just traced, except including contact 60 of relay E¹⁻⁵ instead of contact 59^P.

As soon as relay TE becomes energized, its contact 68 will be opened, causing relay P to be 70 75

deenergized and to, in turn, deenergize indicator i by the opening of contact 69. When relay TE has been energized for a measured period of time, its front contacts will close, and hence a third pick-up circuit will be completed for magnet 27 of lock K^{1-5} , which is the same as the first pick-up circuit as far as contact 54 of lever V^{1-5} , thence passing through contacts 61 E^{1-5} and 62 TE , and winding 27 to terminal o.

10 The leverman can now complete the return of lever V^{1-5} to its N position.

I will assume that all parts of the apparatus are again in their normal condition, and that the leverman then clears signal S^{1a} by moving lever 15 V^{1-5} to its R position, as previously described.

I will also assume that the leverman desires to arrange for a traffic movement from track X over switch W^2 reversed and switch W^1 normal. He will therefore move switch lever VW^2 to its r 20 position, causing the pole-changing contacts 7 and 8 of lever VW^2 to be closed in the r position. With pole-changing contacts 7 and 8 closed in the r position, current of reverse polarity will be supplied to the circuit 25 previously traced for mechanism w^2 , causing this mechanism to move switch W^2 to its reverse position. With switch W^2 in its reverse position, contact 16 operated in conjunction with switch W^2 will complete the circuit for route re- 30 lay A^3 , only a portion of which is shown in the drawings. Relay A^3 will therefore be energized, and will hence close its contact 18. The leverman will now move lever V^3 to its L position, thereby completing a circuit for energizing relay 35 H^3 , this circuit passing from terminal x, through contact 17 of lever V^3 , contact 19 of relay A^3 , and the winding of relay H^3 to terminal o. Relay H^3 , upon becoming energized, completes a circuit through its front contact 63 H^3 for operating the 40 mechanism of signal S^3 to the clear position.

I will further assume that an eastbound train arrives on approach section $a-b$ while signal S^{1a} is in the clear position. I will also assume that the leverman returns signal S^{1a} to the stop position before the train reaches this signal, by returning lever V^{1-5} to its D position where further movement of the lever will be arrested by engagement of dog 28 of lock K^{1-5} with lug 29 of segment 30 of lever V^{1-5} . Relay E^{1-5} will 45 now be energized by its circuit previously traced, and relay TE will also be energized by the circuit previously traced through contact 65 V^{1-5} . Relay TE will therefore be set into operation.

I will now assume that the leverman decides to 50 return signal S^3 to the stop position, and to release lever V^3 as soon as possible. He will therefore return lever V^3 as far as its B position, and will momentarily open the circuit for relay TE by depressing push button contact v^3 , thereby 55 returning relay TE to the deenergized condition, to complete a circuit for relay E^3 . As soon as he permits contact v^3 to again close, relay TE will be again set into operation. Another circuit for relay TE is now closed, in addition to the circuit 60 through contact 65 V^{1-5} . The additional circuit passes from terminal x, through contacts 64 V^3 , 67 T^3 , v^3 , v^{2-4} and v^{1-5} , and the winding of relay TE to terminal o. With lever V^{1-5} still in the D position, relay E^{1-5} is still energized by its stick 65 circuit. The return of lever V^3 to its B position has completed a circuit for relay E^3 , passing from terminal x, through contact 19 of relay H^3 , contact 20 of lever V^3 , contact 23 P , and the winding of relay E^3 to terminal o. Relay E^3 will therefore 70 become energized and complete its stick circuit 75

which is the same as the pick-up circuit just traced except that it includes contact 24 of relay E^3 instead of contact 23 P . As soon as relay TE closes its front contacts, lock K^{1-5} will become energized by the circuit previously traced through contact 62 TE , and lock K^3 will become energized by a circuit passing from terminal x, through contact 19 of relay H^3 , contact 20 of lever V^3 , contacts 25 E^3 and 26 TE , and winding 27 of lock K^3 to terminal o. The leverman can now return both levers V^{1-5} and V^3 to the N position. 10

From the foregoing description of the operation of the first form of apparatus embodying my invention, it follows that time element relay TE is normally deenergized, and that in order to set relay TE into operation to release only one lever, the leverman has only to return that one lever to its lock position, no other manual operation, such as that for opening a push button contact v , being necessary. With relay TE normally deenergized, relay P and indicator i are normally energized. In order to start the release of a second lever before the release of a first lever is completed, the leverman will de- 15 energize relay TE by momentarily opening one of the contacts v , thereby causing the operation of relay TE to start over. 20

The second form of apparatus is the same as the first form except that in the control of relay TE the multiple paths shown to the left of push button contact v^3 in Fig. 2 are omitted as shown in Fig. 2a. Relay TE is therefore normally energized, and must be momentarily deenergized by opening of one of the contacts v in order to be set into operation whenever any lever V is to be 25 released. 30

Assuming, for example, that signal S^{1a} has been cleared as previously described, and that, when an eastbound train arrives in approach section $a-b$, the leverman decides to arrange some 35 other route. He will therefore return lever V^{1-5} to its lock position D, and will then momentarily depress contact v^{1-5} , shown in Fig. 2a, to deenergize relay TE. As soon as contact v^{1-5} is closed, relay TE will be set into operation to again close 40 its front contacts. Contact 68 of relay TE will close as soon as contact v^{1-5} opens the circuit for relay TE, and hence relay P will become energized, thereby completing the circuit previously 45 traced for relay E^{1-5} . Upon the lapse of a measured period of time after the re-energization of relay TE, winding 27 of lock K^{1-5} will 50 become energized by its circuit previously traced, and the leverman can then return lever V^{1-5} to its N position. 55

I will now trace the operation of the third form of apparatus embodying my invention. With the switch levers V in the normal position, and with lock relays M of Fig. 6 energized, normal control circuits are closed for switch mechanisms w as shown in Fig. 3. The circuit for mechanism w^1 , for example, passes from terminal x, through contact 7 of lever VW^1 in the n position, contacts 74 M^4 , 75 M^3 , 76 M^2 , and 77 M^1 , mechanism w^1 , and contact 8 of lever VW^1 in the left-hand position, back to terminal o. 60

Each of the lock relays M is energized by a stick circuit which includes one of its own front contacts. The stick circuit for relay M^1 , for example, passes from terminal x, through contacts 70 113 H^{1a} , 114 H^{1a} , 112 H^{1b} , 113 H^{1b} , contact 115 of relay M^1 , and the winding of relay M^1 to terminal o. A pick-up circuit is also closed for each of the approach locking relays M^1 and M^4 . The pick-up circuit which is closed for relay M^1 , for 75

example, is the same as the stick circuit just traced except that it includes contact 114^{T1} instead of contact 115 of relay M¹.

Relay TE, shown in Fig. 7, is energized by a circuit passing from terminal x, through the front points of contacts 152^{M1}, 157^{M2}, 161^{M3}, 165^{M4}, and 170^{M5}, and the winding of relay TE to terminal o.

I will assume that the leverman clears signal S^{1a} by moving lever V¹⁻⁵, shown in Fig. 4, to its R position. With lever V¹⁻⁵ in its R position, signal relay H^{1a}, shown in Fig. 4, will be energized by a circuit passing from terminal x, through contact 47 of lever V¹⁻⁵ in the R position, contact 48 of relay A^{1a}, and the winding of relay H^{1a} to terminal o. Relay H^{1a}, upon becoming energized, opens its contact 110^{H1a}, thereby deenergizing approach locking relay M¹. With relay M¹ deenergized, the circuits for mechanisms w for the switches in the route governed by signal S^{1a}, and also for some switches in conflicting routes, will open, and hence no operation of these switches can take place. For example, the circuit for mechanism w¹ for switch W¹ of a conflicting route will be open at contact 77^{M1}. With relay H^{1a} energized, and with relay M¹ deenergized, relay TE is retained in the energized condition by a circuit which is the same as the circuit previously traced for this relay except that it includes contact 153^{H1a} and the back point of contact 152^{M1} instead of the front point of contact 152^{M1}. Relay H^{1a}, upon becoming energized, also closes its contact 84^{H1a}, thereby completing a circuit for energizing relay h^{1a}, this circuit passing from terminal x, through contacts 83^{H5} and 84^{H1a}, and the winding of relay h^{1a} to terminal o. Relay h^{1a}, upon becoming energized, opens its contact 111^{h1a} in the circuit for relay M¹ which is, however, already open at contact 110^{H1a}. With relay h^{1a} energized, a circuit including a contact 100^{h1a} similar to the circuit shown for signal S³, will be closed for operating the arm of signal S^{1a} to the clear position.

I will assume that the leverman desires to return the arm of signal S^{1a} to the stop position before a train arrives on approach section a-b. He will therefore return lever V¹⁻⁵ to its N position, thereby deenergizing relays H^{1a} and h^{1a}. The arm of signal S^{1a} will therefore be returned to the stop position, and the pick-up circuit previously traced for relay M¹ will be completed. Relay M¹ will now again close its contact 152^{M1} at the front point. The apparatus can be so arranged that the interval of time between the opening of contact 153^{H1a} and the closing of contact 152^{M1} at the front point will not be sufficient to cause relay TE to be deenergized and then set into operation.

I will assume that the leverman, after all parts of the apparatus have been again returned to the normal condition, again clears signal S^{1a}. An eastbound train, upon entering section a-b and then passing signal S^{1a}, will complete a third circuit for relay TE, which is the same as the first circuit traced for this relay except that it includes contact 155^{T2} and the back point of contact 152^{M1} instead of the front point of contact 152^{M1}. Relay TE will therefore be retained in the energized condition by this third circuit. If the leverman returns lever V¹⁻⁵ to the N position while the train is in the detector section b-c, approach locking relay M¹ will become energized by a second pick-up circuit which is

the same as the pick-up circuit previously traced except that it includes contact 116^{T2} instead of contact 114^{T1}.

I will now assume that, after all parts of the apparatus have again been returned to the normal condition, the leverman again clears signal S^{1a} as before. I will also assume that after a train has entered approach section a-b, but before it has passed signal S¹⁻⁵, the leverman returns lever V¹⁻⁵ to the N position. With a train occupying section a-b, contact 114^{T1} in the first pick-up circuit for relay M¹ will be open, and with the detector section unoccupied, the second pick-up circuit for relay M¹ will be open at contact 116^{T2}.

With relay M¹ thus deenergized, and with relay H^{1a} deenergized while contact 155^{T2} is open, relay TE will become deenergized, thereupon completing a circuit through its contact 68 for energizing relay P. With relay P energized, a pick-up circuit will be closed for energizing release relay F¹, this circuit passing from terminal x, through contacts 110^{H1a}, 111^{h1a}, 112^{H1b}, 113^{h1b}, 119^{M1}, and 120^P, and the winding of relay F¹ to terminal o. Relay F¹, upon becoming energized by the circuit just traced, completes its own stick circuit which is the same as the pick-up circuit except that it includes contact 121 of relay F¹ instead of contact 120^P. With relay F¹ energized, relay TE will be set into operation by a circuit which is the same as the circuit first traced for this relay except that it includes contact 156^{F1} and the back point of contact 152^{M1} instead of the front point of contact 152^{M1}. When relay TE has been in operation for a measured period of time, contact 117TE will close, and will thereby complete a third pick-up circuit for relay M¹, which is the same as the first pick-up circuit traced for this relay except that it includes contacts 117TE and 118^{F1} instead of contact 114^{T1}.

With relay M¹ energized, the control circuits for the switches in the route governed by signal S^{1a}, or in conflicting routes, will be closed. For example, the circuit for mechanism w¹ for switch W¹ will now be closed at contact 77^{M1} which was open when relay M¹ was deenergized.

I will next assume that all parts of the apparatus are again returned to the normal condition, and that the leverman then again clears signal S^{1a} as previously described.

I will also assume that he reverses switch W². To do this, he will move lever VW² to its r position, thereby supplying current of reverse polarity to the circuit for mechanism w² on account of pole-changing contacts 7 and 8 of lever VW² being moved to the r position. Relay A³ will therefore become energized.

The leverman will clear signal S³ by moving lever V³ to its L position, thereby completing the circuit shown in Fig. 4 for relay H³, this circuit passing from terminal x, through contact 17 of lever V³, contact 18 of relay A³, and the winding of relay H³ to terminal o. Relay H³, upon becoming energized, opens its contact 122^{H3} in the circuits for relay M³, causing relay M³ to become deenergized. With relay H³ energized, and with relay M³ deenergized, relay TE will be retained in the energized condition by a circuit passing through contact 162^{H3} and the back point of contact 161^{M3} instead of the front point of contact 161^{M3} in one of the circuits previously traced for relay TE.

I will further assume that an eastbound train enters section a-b, and that the leverman returns lever V¹⁻⁵ to the N position before the train reaches signal S^{1a}. Operation of time element 75.

relay TE will therefore be started by the circuit which includes contact 156^{F1} and the back point of contact 152^{M1}.

I will also assume that before relay TE has closed its front contacts, the leverman returns signal S³ to the stop position by moving lever V³ to its N position. With relay H³ now deenergized, relay TE will be deenergized because of the opening of contact 162^{H3}.

With relay TE deenergized, relay P will become energized by its circuit through contact 68 of relay TE, relay P thereby completing a circuit for relay F³, passing from terminal x, through contacts 122^{H3}, 123^{H3}, 128^{M3}, and 129^P, and the winding of relay F³ to terminal o. Relay F³, upon becoming energized, completes its stick circuit which is the same as the pick-up circuit just traced except including its own contact 130 instead of contact 129^P. Relay F³, upon becoming energized, completes another circuit for relay TE, which includes contact 164^{F3} and the back point of contact 161^{M3}. When relay TE has been in operation for a measured period of time, the front contacts of relay TE will become closed. Relay M¹ will therefore become energized by its pick-up circuit previously traced through contacts 117TE and 118^{F1}, and relay M³ will become energized by a circuit passing from terminal x, through contacts 122^{H3}, 123^{H3}, 126TE, and 127^{F3}, and the winding of relay M³ to terminal o.

From the foregoing description of the operation of the third form of apparatus embodying my invention, it follows that relay TE is normally energized, and that it is retained in the energized condition at all times except when a signal 1 is returned to the stop position while a train is approaching this signal in section a—b, or when a signal 4 is returned to the stop position while a train is approaching in section e—f, or when any one of the signals S², S³ and S⁵, with which no approach locking is associated, is returned to the stop position before a train passes the corresponding signal. In order to set relay TE into operation to release any one of the locking relays M, the leverman has only to return an associated signal lever to its N position, no other manual operation being necessary. If relay TE is already in operation for picking up another relay M when the leverman desires to pick up a second relay M, he has only to return the lever associated with the second relay M to its normal position, thereby stopping the operation of the relay TE, and then starting another operation of this relay. Upon completion of the new operation of relay TE, both relays M will be picked up. With relay TE energized, relay P and indicator i will be deenergized.

The fourth form of apparatus embodying my invention is the same as the third form except that the circuit arrangement of Fig. 2^a is used instead of that of Fig. 7. Therefore, whenever any one of the release relays F is to be energized for picking up a corresponding lock relay M, the leverman must open one of the push button contacts v, as well as return an associated lever V to its N position.

I will assume, for example, that signal S^{1a} has been cleared as previously described, and that when a train arrives in approach section a—b, the leverman decides to arrange some other route. Accordingly, he will first return lever V^{1—5} to its N position, and will then depress push button contact v^{1—5} to deenergize relay TE and set it into operation to close its front contacts.

After the deenergization of relay TE, the corresponding relay F¹ will become energized as previously described. Upon the lapse of a measured period of time, during which relay TE is in operation, relay M¹ will become energized by its circuit through contacts 117TE and 118^{F1}, as previously described. 5

I have described, for a few typical traffic movements, the operation of each of four forms of apparatus embodying my invention. From those descriptions of operation, and from the preceding general description, operation of each of the four forms of apparatus for every other possible traffic movement will be readily understood by reference to the drawings. 10

In conclusion, with the first form of apparatus embodying my invention for group releasing means for signal lever locks or for locking relays, only the usual manual operation of a signal lever is required for setting time element means into operation for releasing any one signal lever lock or locking relay. If it is necessary to interrupt the operation of the time element means in order to prepare for releasing a second signal lever lock or locking relay, a push button contact v must be operated in addition to the operation of the signal lever. 15

With the second and fourth forms of apparatus embodying my invention, manual operation of a push button contact v is required in addition to operation of a signal lever whenever a time element relay TE is to be set into operation for releasing a signal lever lock or locking relay. 20

With the third form of apparatus embodying my invention, only the usual operation of a signal lever is required to set a time element relay TE into operation for releasing one or more signal lever locks or locking relays. 25

Although I have herein shown and described only four forms of interlocking control apparatus embodying my invention, it is understood that various changes and modifications may be made therein within the scope of the appended claims without departing from the spirit and scope of my invention. 30

Having thus described my invention, what I claim is:

1. In combination, a railway track switch, a signal for governing traffic movements over said switch, manually controllable means for operating said switch, a manually operable signal lever having a normal and a reverse position and also a normal indication position, means controlled by said lever in its reverse position for clearing said signal to permit a traffic movement over said switch, means controlled by said lever when moved from its normal position for preventing operation of said switch, means controlled by a train approaching said signal for preventing return of said signal lever from its reverse position beyond its normal indication position, a time element device set into operation by the return of said signal lever to its normal indication position while a train is approaching said signal, a stick relay, a pick-up circuit for said stick relay controlled by said lever and by said time element device and closed when said lever is returned to its normal indication position, a stick circuit for retaining said stick relay in the energized condition independently of the condition of said time element device as long as said lever remains in the normal indication position, and means controlled by said stick relay and by said time element device for releasing said lever and thereby permitting return of said lever to its 40

normal position when said time element device has been operated a measured period of time.

2. In combination, a railway track switch, a signal for governing traffic movements over said switch, manually controllable means for operating said switch, a manually operable signal lever having a normal and a reverse position and also a normal indication position, means controlled by said lever in its reverse position for clearing said signal to permit a traffic movement over said switch, means controlled by said lever when moved from its normal position for preventing operation of said switch, means controlled by a train approaching said signal for preventing return of said signal lever from its reverse position beyond its normal indication position, a time element device set into operation by the return of said signal lever to its normal indication position while a train is approaching said signal, a stick relay, a pick-up circuit for said stick relay controlled by said lever and by said time element device and closed when said lever is returned to its normal indication position, a stick circuit for retaining said stick relay in the energized condition independently of the condition of said time element device as long as said lever remains in the normal indication position, means controlled by said stick relay and by said time element device for releasing said lever to permit return of said lever to its normal position when said time element device has been operated a measured period of time, and means controlled by said lever in its normal indication position for retaining said lever in its released condition independently of the condition of said stick relay or said time element device.

3. In combination, a stretch of railway track, a signal for governing traffic movements over said stretch, a second traffic governing device, manually controllable means for operating said second traffic governing device for directing traffic movements over said stretch, a manually operable signal lever having a normal and a reverse position, means controlled by said lever in its reverse position for clearing said signal, means controlled by said lever when moved from its normal position for preventing operation of said second traffic governing device, means controlled by a train approaching said signal for preventing complete return of said lever to its normal position, a time element device, manually controlled means for at times setting said time element device into operation, a stick relay, a pick-up circuit for said stick relay controlled by said lever and by said time element device and closed at the time an operation of said time element device is started when said lever is returned part way to its normal position, a stick circuit controlled by said lever for retaining said stick relay in the energized condition independently of the condition of said time element device, and means controlled by said stick relay in its energized condition and by said time element device for releasing said lever and thereby permitting complete return of said lever to its normal position when said time element device has been operated a measured period of time.

4. In combination, a stretch of railway track, a signal for governing traffic movements over said stretch, a second traffic governing device, manually controllable means for operating said second traffic governing device for directing traffic movements over said stretch, a manually operable signal lever having a normal and a reverse position, means controlled by said lever in its reverse posi-

tion for clearing said signal, means controlled by said lever when moved from its normal position for preventing operation of said second traffic governing device, means automatically controlled to prevent return of said lever to its normal position, a time element device, manually controlled means for at times setting said time element device into operation, a stick relay, a pick-up and a stick circuit for said stick relay one of which is controlled by said time element device in a first condition and the other of which is manually controlled independently of the condition of said time element device, and means controlled by said stick relay in its energized condition and by said time element device for releasing said lever and thereby permitting return of said lever to its normal position when said time element device has been operated a given measured period of time to a second condition.

5. In combination, a plurality of railway traffic routes, a plurality of signals for governing traffic movements over said traffic routes, a manually operable control lever for each of said signals each having a normal and a reverse position, a plurality of other traffic governing devices, manually controllable means for operating said other traffic governing devices for directing traffic movements over said routes, means controlled by each of said levers in its reverse position for clearing an associated signal, means controlled by each of said levers when moved from its normal position for preventing operation of one or more of said other traffic governing devices or of another of said signals, automatically operated means associated with each of said levers for at times preventing return of the associated lever to its normal position, a time element device, manually controllable means associated with each of said levers for at times setting said time element device into operation, a stick relay for each of said levers, a pick-up and a stick circuit for each of said stick relays, one of said circuits controlled by said time element device in a first condition and the other of said circuits controlled by the associated lever between its normal and reverse positions independently of the condition of said time element device, and means controlled by said time element device and by one of said stick relays for releasing the associated lever and thereby permitting return of the associated lever to its normal position when said time element device has been operated a given measured period of time after the associated stick relay became energized.

6. In combination, a plurality of railway traffic routes, a plurality of signals for governing traffic movements over said traffic routes, a manually operable control device for each of said signals, a plurality of other traffic governing devices, manually controllable means for operating said other traffic governing device for directing traffic movements over said routes, means controlled by each of said control devices upon being operated for clearing an associated signal and for preventing operation of one or more of said other traffic governing devices or of another of said signals, a time element device, manually controllable means associated with each of said manually operable control devices for at times setting said time element device into operation, a stick relay for each of said manually operable control devices, a pick-up and a stick circuit for each of said stick relays one of said circuits controlled by said time element device in a first condition and the other of said circuits controlled by the associated manual-

- ly operable control device independently of the condition of said time element device, and means controlled by said time element device and by each of said stick relays for releasing one or more of said other traffic governing devices or of said signals when said time element device has been operated from said first condition a given measured period of time after the associated stick relay became energized.
7. In combination, a plurality of railway traffic routes, a plurality of signals for governing traffic movements over said traffic routes, a manually operable control device for each of said signals each having a normal and a reverse position, a plurality of other traffic governing devices for said routes, means controlled by each of said manually operable control devices in its reverse position for clearing an associated signal, manually controllable means for operating said other traffic governing devices for directing traffic movements over said routes, a locking stick relay for each of said signals, a release stick relay for each of said locking stick relays, a time element device, manually controllable means associated with each of said release stick relays for at times setting said time element device into operation, a pick-up and a stick circuit for each of said release stick relays one of said circuits controlled by the associated manually operable control device in its normal position and by said time element device in its deenergized condition and the other of said circuits controlled by the associated manually operable control device in its normal position independently of the condition of said time element device until said time element device has been operated a measured period of time, a pick-up and a stick circuit for each of said locking stick relays one of which circuits is controlled by said time element device and by the associated release stick relay and the other of which is controlled by the associated manually operable control device in its normal position and means controlled by each of said locking stick relays which when its locking stick relay is deenergized prevents operation of one of said other traffic governing devices or of another signal.
8. In combination, a plurality of railway traffic routes, a plurality of signals for governing traffic movements over said traffic routes, a manually operable control device for each of said signals, a plurality of other traffic governing devices for said routes, means controlled by each of said manually operable control devices for clearing an associated signal, manually controllable means for operating said other traffic governing devices for directing traffic movements over said routes, a locking stick relay for each of said signals, a release stick relay for each of said locking stick relays, a time element device having a first condition and an operated condition, means controlled by each of said release stick relays when energized for at times setting said time element device into operation from the first condition to the operated condition, a pick-up and a stick circuit for each of said release stick relays one of said circuits controlled by the associated locking stick relay in the deenergized condition and by said time element device in its first condition and the other controlled by the associated locking stick relay in the deenergized condition, a pick-up and a stick circuit for each of said locking stick relays one of which circuits is controlled by said time element device in its operated condition and by the associated release stick relay in the energized

condition and the other of which is controlled by the associated manually operable control device, and means controlled by each of said locking stick relays which when its locking stick relay is deenergized prevents operation of one or more of said other traffic governing devices or of another signal.

9. In combination, a railway track switch, a signal for governing traffic movements over said switch, a manually controllable device, means controlled by said device for at times clearing said signal to permit a traffic movement over said switch, manually controllable means for operating said switch, means controlled by said device when said signal is cleared for preventing operation of said switch, means controlled by a train approaching said signal for at times preventing release of said switch by said manually controllable device, a time element device at times set into operation through the return of said signal to the stop condition by said manually controllable device, a stick relay, a pick-up circuit for said stick relay controlled by said manually controllable device and by said time element device and closed when said manually controllable device is returned to the condition for causing said signal to indicate stop, a stick circuit for retaining said stick relay in the energized condition until said time element device has been operated a measured period of time, and means controlled by said time element device when operated a measured period of time and by said stick relay when energized for releasing said switch.

10. In combination, a stretch of railway track, a signal for governing traffic movements over said stretch, a second traffic governing device for governing traffic movements over said stretch, a manually controllable device having a first and a second position, manually controllable means for operating said second traffic governing device for governing traffic movements over said stretch, means controlled by said manually controllable device in its second position for clearing said signal and for preventing operation of said second traffic governing device, means controlled by a train approaching said signal for preventing operation of said second traffic governing device when said manually controllable device is returned to its first position, a time element device having a first and a second condition, manually controllable means for at times setting said time element device into operation from its first to its second condition, a stick relay, a pick-up circuit for said stick relay controlled by said time element device in its first condition, a stick circuit for said stick relay controlled by said manually controllable device and closed when said manually controllable device is moved away from its second position, and means controlled by said stick relay when energized and by said time element device for releasing said second traffic governing device when said time element device has been operated a measured period of time to its second condition.

11. In combination, a section of railway track including a switch, a signal for governing traffic movements over said switch, manually controllable means for clearing said signal, a locking stick relay, a release stick relay, a time element relay, a pick-up circuit for said locking stick relay closed by a train entering said section, a stick circuit for retaining said locking stick relay in the energized condition if said manually controllable means is not in condition for clearing said signal, a manually controllable circuit for energizing said time

element relay, a pick-up circuit effective to energize said release stick relay if said time element relay is deenergized while said locking stick relay is deenergized and said manually controllable means is not in condition for clearing said signal, a stick circuit for retaining said release stick relay energized independently of the condition of said time element relay until said locking stick relay becomes energized, a second pick-up circuit effective to energize said locking stick relay if said release stick relay is energized and if said time element relay has been energized a given measured period of time after energization of said release stick relay, and means controlled in part by said locking stick relay for operating said switch only if said locking stick relay is energized.

12. In combination, a stretch of railway track including a switch, a signal for governing traffic movements over said switch, manually controllable means operable to a control condition for clearing said signal, manually controlled switch apparatus for operating said switch, locking means operable to a locking condition by said manually controllable means for preventing operation of said switch when said manually controllable means is operated to clear said signal, a time element device, a circuit normally closed for energizing said time element device but which is opened by said locking means when said locking means is put into said locking condition, a second circuit closed by said manually controllable means for retaining said time element device in the energized condition while said manually controllable means is in said control condition, a third circuit closed by a train entering said stretch for retaining said time element device in the energized condition while said locking means is in said locking condition, release means operable to a releasing condition, a fourth circuit closed by said release means in its releasing condition for operating said time element device, means controlled by said locking means and by said time element device for operating said release means to its releasing condition if said time element device is deenergized while said locking means is in its locking condition, and means controlled by said release means in its releasing condition for restoring said locking means to its non-locking condition when said time element device has been operated a measured period of time by said fourth circuit.

13. In combination, a stretch of railway track including a switch, a signal for governing traffic movements over said switch, manually controllable means operable to a control condition for clearing said signal, manually controlled switch apparatus for operating said switch, locking means operable to a locking condition by said manually controllable means for preventing operation of said switch when said manually controllable means is operated to clear said signal, a time element device, a circuit normally closed for energizing said time element device but which is opened by said locking means when said locking means is put into said locking condition, release means operable to a releasing condition, a second circuit closed by said release means in its releasing condition for energizing said time element device, means controlled by said locking means and by said time element device for operating said release means to its releasing condition if said time element device is deenergized while said locking means is in its locking condition, and means controlled by said release means in its releasing condition for restoring said lock-

ing means to its non-locking condition when said time element device has been energized a measured period of time.

14. In combination, a plurality of railway tracks interconnected by switches to form a plurality of traffic routes, a plurality of signals for governing traffic movements over said routes, a manually controllable device for each of said signals each operable to a control condition for clearing its signal, manually controllable means for operating said switches, a locking device for each of said signals each operable to a locking condition by the manually controllable device for the associated signal for preventing operation of the switches in the route governed by the associated signal when its manually controllable device is in the control condition, a time element device, means controlled by each of said manually controllable devices when withdrawn from its control condition and by each of said locking devices when in its locking condition for setting said time element device into operation, and means controlled by said time element device and by each of said manually controllable devices when withdrawn from its control condition for releasing the associated locking device upon the lapse of a measured period of time after the beginning of the operation of said time element device.

15. In combination, a plurality of railway tracks interconnected by switches to form a plurality of traffic routes, a plurality of signals for governing traffic movements over said routes, a manually operable lever for each of said signals each operable from a normal position to a reverse position for clearing its signal, manually controlled means for operating said switches between their extreme positions, a locking relay for each of said signals each of which becomes deenergized by operation of the lever for the associated signal to its reverse position, means controlled by each of said locking relays when deenergized for preventing operation of the switches in the route governed by the associated signal, a time element relay, means controlled by each of said signal levers when withdrawn from its reverse position and by each of said locking relays when deenergized for setting the mechanism of said time element relay into operation, and means controlled by said time element relay and by each of said signal levers when withdrawn from its reverse position for energizing the associated locking relay when said time element relay has been operated a measured period of time.

16. In combination, a plurality of railway tracks interconnected by switches to form a plurality of traffic routes, a plurality of signals for governing traffic movements over said routes, a manually operable lever for each of said signals each operable from a normal position to a reverse position for clearing its signal, manually controllable means for operating said switches between their extreme positions, a normally energized locking device for each of said signals each of which becomes deenergized by operation of the lever for the associated signal to its reverse position, means controlled by each of said locking devices preventing operation of the switches in the route governed by the associated signal when the locking device is deenergized, a time element relay, a normally closed circuit for energizing said time element relay, manually operable means for opening said circuit to deenergize said time element relay and for afterward closing said circuit, and means controlled by said time element relay and by each of said signal levers when

withdrawn from its reverse position for energizing the associated locking device when said time element relay has again been energized a measured period of time.

5 17. In combination, a plurality of railway tracks interconnected by switches to form a plurality of traffic routes, a plurality of signals for governing traffic movements over said routes, a manually operable lever for each of said signals 10 each operable from a normal position to a reverse position for clearing its signal, manually controllable means for operating said switches between their extreme positions, a normally energized locking relay for each of said signals each 15 of which becomes deenergized by operation of the lever for the associated signal to its reverse position, means controlled by each of said locking relays preventing operation of the switches in the route governed by the associated signal when the 20 locking relay is deenergized, group releasing means for a given group of said locking relays comprising one time element relay for the group and a slow release relay for each of the locking relays in the group, a circuit controlled by front 25 contacts of said locking relays for normally energizing said time element relay, means controlled by each of said signal levers in its reverse position or by a train occupying an associated route for retaining said time element relay en- 30 ergized for normal train movements but causing said time element relay to be deenergized if a signal lever is withdrawn from the reverse position while a train is approaching its signal, means controlled by said time element relay upon be- 35 coming deenergized while any one of said locking relays is deenergized for energizing the associated slow release relay, means controlled by each of said slow release relays in the energized condition for energizing said time element relay, and 40 means controlled by said time element relay and by each of said slow release relays for energizing an associated locking relay when said time element relay has been energized a measured period of time.

45 18. In combination, a plurality of railway tracks interconnected by switches to form a plurality of traffic routes, a plurality of signals for governing traffic movements over said routes, a manually operable lever for each of said signals 50 each operable from a normal position to a reverse position for clearing its signal, manually controllable means for operating said switches between their extreme positions, a normally energized locking device for each of said signals each of which becomes deenergized by operation of the lever for the associated signal to its reverse position, means controlled by each of said locking devices preventing operation of the switches in the route governed by the associated signal when the locking device is deenergized, group releasing means for said locking devices comprising one time element relay for all of 55 said locking devices and a release relay for each of said locking devices, means controlled by each of said levers when withdrawn from its reverse position and by the associated locking device in its deenergized condition for energizing the associated release relay, manually controllable means for energizing said time element relay, and means controlled by said time element relay and by each of said release relays for energizing an associated locking device when said time element relay has been energized a measured period of time.

75 19. In combination, a plurality of railway

tracks interconnected by switches to form a plurality of traffic routes, a plurality of signals for governing traffic movements over said routes, a manually operable lever for each of said signals each operable from a normal position to a reverse position for clearing its signal, manually controllable means for operating said switches between their extreme positions, a normally energized locking device for each of said signals each of which becomes deenergized by operation of the lever for the associated signal to its reverse position, means controlled by each of said locking devices preventing operation of the switches in the route governed by the associated signal when the locking device is deenergized, group releasing means for said locking devices comprising one time element device for all of said locking devices and a release relay for each of said locking devices, means controlled by each of said levers when withdrawn from its reverse position and by said time element device when deenergized for energizing the associated release relay, manually controllable means for energizing said time element device, and means controlled by said time element device and by each of said release relays for energizing an associated locking device when said time element device has been energized a measured period of time.

20. In combination, a selector relay, an electroresponsive device, a time element device, manually controllable means for energizing said selector relay, means preventing the selector relay from becoming energized except when the time element device has been deenergized, means effective when the selector relay is energized to energize the time element device, and means controlled by said selector relay for energizing said electroresponsive device while said selector relay is energized when said time element device has been energized a measured period of time.

21. In combination, a selector relay, an electroresponsive device, a time element device, a manually controllable device, means controlled by said manually controllable device for energizing said selector relay, means preventing the selector relay from becoming energized except when the time element device has been deenergized, means controlled by said manually controllable device for energizing the time element device contemporaneously with said selector relay, and means controlled by said selector relay for energizing said electroresponsive device while said selector relay is energized when said time element device has been energized a measured period of time.

22. In combination, a selector relay, an electroresponsive device, a time element device, a manually controllable device, means controlled by said manually controllable device for energizing said selector relay, means preventing the selector relay from becoming energized except when the time element device has been deenergized, a second manually controllable device, a circuit controlled by said second manually controllable device for energizing said time element device, and means controlled by said selector relay for energizing said electroresponsive device while said selector relay is energized when said time element device has been energized a measured period of time.

23. In combination, a selector relay, an electroresponsive device, a time element device, a manually controllable device, means controlled by said manually controllable device for energizing

5 said selector relay, means preventing the selector relay from becoming energized except when the time element device has been deenergized, means controlled by the selector relay when energized to energize the time element device, and means controlled by said time element device for energizing said electroresponsive device while said time element device is energized when the time element device has been energized a measured 10 period of time.

10 24. In combination, a plurality of selector relays, an electroresponsive device for each of said selector relays, a time element device, a manually controllable device for each of said selector 15 relays, means controlled by each of said manually controllable devices for energizing the associated selector relay, means preventing the energization of any selector relay except under the control of said time element device in its deenergized condition, means controlled by said selector relays for energizing said time element device when any one of said selector relays is energized, means controlled by an associated manually controllable device for retaining each 20 selector relay energized while said time element device is energized, and means controlled by said time element device when it has been energized a measured period of time and by each of said selector relays in its energized condition for energizing an associated electroresponsive device.

25 25. In combination, a plurality of railway tracks interconnected by switches to form a plurality of traffic routes, a plurality of signals for governing traffic movements over said traffic routes, a plurality of normally energized locking relays associated with said traffic routes, manually controllable means controlled also in part by said locking relays for moving each of said switches from either of its extreme positions to the other only if given associated said locking 30 relays are energized, manually controllable means for clearing each of said signals for permitting a traffic movement to be made over an associated route, means associated with each of said signals for deenergizing an associated said locking relay when the corresponding signal is controlled to indicate otherwise than stop, a time element device, means associated with each of said signals for energizing said time element device when the signal is again controlled to indicate stop, and means controlled by said time element device for energizing a corresponding locking relay upon the lapse of a measured period of time after each signal is controlled to indicate stop.

35 26. In combination, a plurality of railway tracks interconnected by switches to form a plurality of traffic routes, a plurality of signals for governing traffic movements over said traffic routes, a plurality of normally energized locking relays associated with said traffic routes, manually controllable means controlled also in part by said locking relays for moving each of said switches from either of its extreme positions to the other only if given associated said locking relays are energized, manually controllable means for clearing each of said signals for permitting a traffic movement to be made over an associated route, means associated with each of said signals for deenergizing an associated said locking relay when the corresponding signal is controlled to indicate otherwise than stop, a time element device, means associated with each of said signals for energizing said time element device when the signal is again controlled to indicate stop, manually operable means for momentarily interrupting the energization of said time element device, and means controlled by said time element device for energizing one or more of said locking relays upon the lapse of a measured period of time after such momentary interruption of the energization of said time element device.

5 27. In combination, a plurality of railway tracks interconnected by switches to form a plurality of traffic routes, a plurality of signals for governing traffic movements over said traffic routes, a plurality of normally energized locking relays associated with said traffic routes, manually controllable means controlled also in part by said locking relays for moving each of said switches from either of its extreme positions to the other only if given associated said locking relays are energized, manually controllable means for clearing each of said signals for permitting a traffic movement to be made over an associated route, means associated with each of said signals for deenergizing an associated said locking relay when the corresponding signal is controlled to indicate otherwise than stop, a normally energized time element device, means associated with each of said signals for momentarily interrupting the energization of said time element device when the signal is again controlled to indicate stop, and means controlled by said time element device for energizing one or more said locking relays upon the lapse of a measured period of time after such momentary interruption of the energization of said time element device.

10 28. In combination, a plurality of railway tracks interconnected by switches to form a plurality of traffic routes, a plurality of signals for governing traffic movements over said traffic routes, a plurality of manually operable signal levers each having a normal position and one or more reverse 15 positions, an electric lever lock for each of said signal levers which if deenergized prevents movement of its lever from a reverse position to the normal position, manually controllable means for moving each of said switches from either of its extreme positions to the other only if given said signal levers are in the normal position, means controlled by each of said signal levers when moved to a reverse position for clearing an associated signal, a time element device, means controlled by each of said signal levers for energizing said time element device when an attempt is made to return the signal lever from a reverse position to its normal position, and means controlled by said time element device for energizing one or more of said signal lever locks upon the lapse of a measured period of time after an attempt has been made to restore one of said signal levers to the normal position.

20 29. In combination, a plurality of parallel railway traffic routes interconnected by switches and provided with signals for governing traffic movements over said routes, a stick relay for each of said routes, a pick-up circuit for each of said stick relays controlled by given traffic conditions 25 for energizing the corresponding stick relay if a signal for the same route is controlled to indicate stop, a stick circuit for each of said stick relays for retaining the corresponding stick relay in its energized condition independently of said given traffic conditions as long as a signal for the same route is controlled to indicate stop, group control apparatus for said stick relays comprising a manually controllable time releasing device as well as a plurality of slow release relays one for 30

35 30. In combination, a plurality of parallel railway traffic routes interconnected by switches and provided with signals for governing traffic movements over said routes, a stick relay for each of said routes, a pick-up circuit for each of said stick relays controlled by given traffic conditions 35 for energizing the corresponding stick relay if a signal for the same route is controlled to indicate stop, a stick circuit for each of said stick relays for retaining the corresponding stick relay in its energized condition independently of said given traffic conditions as long as a signal for the same route is controlled to indicate stop, group control apparatus for said stick relays comprising a manually controllable time releasing device as well as a plurality of slow release relays one for 40

45 45. In combination, a plurality of parallel railway traffic routes interconnected by switches and provided with signals for governing traffic movements over said routes, a stick relay for each of said routes, a pick-up circuit for each of said stick relays controlled by given traffic conditions 50 for energizing the corresponding stick relay if a signal for the same route is controlled to indicate stop, a stick circuit for each of said stick relays for retaining the corresponding stick relay in its energized condition independently of said given traffic conditions as long as a signal for the same route is controlled to indicate stop, group control apparatus for said stick relays comprising a manually controllable time releasing device as well as a plurality of slow release relays one for 55

each of said parallel routes, means controlled by said time releasing device in a given initial condition for energizing each of said slow release relays, a retaining circuit for each of said slow release relays for retaining its slow release relay in the energized condition while the stick relay for the same route remains deenergized, means controlled by said time element device and by each of said slow release relays for energizing the stick relay for the same route after said time element device has been operated away from said given initial condition for a measured period of time, manually controllable apparatus controlled in part by said stick relays for operating said switches, and manually controllable means for clearing said signals and for controlling said signals to indicate stop.

30. In combination, a plurality of parallel railway traffic routes interconnected by switches and provided with signals for governing traffic movements over said routes, a stick relay for each of said routes, a pick-up circuit for each of said stick relays controlled by given traffic conditions, a stick circuit for each of said stick relays for retaining the corresponding stick relay in its energized condition as long as a signal for the same route is controlled to indicate stop, group control apparatus for said stick relays comprising a manually controllable time element device as well as a plurality of slow release relays one for each of said parallel routes, means controlled by said time element device in a given initial condition for energizing each of said slow release relays, a retaining circuit for each of said slow release relays for retaining its slow release relay in the energized condition while the stick relay for the same route remains deenergized, means controlled by said time element device and by each of said slow release relays for energizing the stick relay for the same route after said time element device has been operated away from said given initial condition for a measured period of time, manually controllable apparatus controlled in part by said stick relays for operating said switches, and manually controllable means for at times clearing said signals.

31. In combination, a plurality of parallel railway traffic routes interconnected by switches and provided with signals for governing traffic movements over said routes, switch locking apparatus for each of said routes operable from a second to a first condition under control by given traffic conditions, manually controllable apparatus for operating each of said switches, means controlled by the switch locking apparatus for each route to permit operation of a corresponding switch when said switch locking apparatus is in said first condition but to prevent operation of the corresponding switch when said switch locking apparatus is in its second condition, group control apparatus for said switch locking apparatus comprising a manually controllable time element device as well as a plurality of stick relays one for each of said parallel routes, means controlled by said time element device in a given initial condition for energizing each of said stick relays, a stick circuit for each of said stick relays for retaining its stick relay in the energized condition while a signal for the same route is controlled to indicate stop, means controlled by said time element device and by each of said stick relays for operating the switch locking apparatus for the corresponding route to said first condition independently of said given traffic conditions when said time element device has been operated away from

said given initial condition for a measured period of time, and manually controllable means for at times clearing said signals.

32. In combination, stick locking apparatus for a plurality of parallel railway traffic routes each of which is provided with switches and with signals for governing traffic movements in both directions, said stick locking apparatus comprising a stick locking relay for each direction of traffic movement over each of the parallel routes and a pick-up circuit for each of said stick locking relays which is closed by the entrance of a train into the associated traffic route as well as a stick circuit for each of said stick locking relays controlled in conjunction with an associated signal for retaining its stick locking relay in the energized condition as long as the associated signal continues to indicate stop, group releasing apparatus for said stick locking apparatus comprising a manually controllable time releasing device as well as a plurality of slow release relays each controlled by the time releasing device to become energized if one of the stick locking relays is deenergized and also means controlled by said slow release relays and by said time releasing device for energizing each of said stick locking relays upon the lapse of a given minimum period of time after an associated signal has been controlled to indicate stop, manually controllable switch operating apparatus for said switches controlled in part by said stick locking relays, and manually controllable means for at times clearing said signals.

33. In combination, stick locking apparatus for a plurality of parallel railway traffic routes each of which includes one or more switches and is provided with signals for governing traffic movements in both directions, said stick locking apparatus comprising a stick locking relay for each direction of traffic movement over each of the parallel routes and means for energizing each of said stick locking relays under given traffic conditions as well as means for retaining each of said stick locking relays in the energized condition as long as an associated signal is controlled to indicate stop, group control apparatus for said stick locking relays comprising a manually controllable time element device and a plurality of locking release relays, means controlled by said time element device in a given initial condition for energizing each of said locking release relays, means controlled in conjunction with said signals for retaining each of said locking release relays in the energized condition while an associated signal is controlled to indicate stop, means controlled by said time element device and by a corresponding locking release relay for energizing each of said locking stick relays when said time element device has been operated away from said initial condition a measured period of time, manually controllable apparatus controlled in part by said stick locking relays for operating said switches, and manually controllable means for at times clearing said signals.

34. In combination, a plurality of parallel railway traffic routes interconnected by switches and each route provided with signals for governing traffic movements in opposite directions, switch locking apparatus for said routes comprising a stick relay for each direction of traffic movement over each of said parallel routes and means controlled by given traffic conditions for energizing each of said stick relays if an associated signal indicates stop as well as means for retaining each of said stick relays in its energized condition in-

dependently of said given traffic conditions as long as an associated signal continues to indicate stop, group releasing apparatus for said switch locking apparatus comprising a manually controllable time releasing device as well as a plurality of slow release relays each of which is controlled by the time releasing device and also means controlled by each of said slow release relays for energizing each of said stick relays upon the lapse 10 of a given minimum period of time after the associated signal has been controlled to indicate stop, manually controllable apparatus controlled in part by said switch locking apparatus for operating said switches, and manually controllable 15 means for at times clearing said signals.

35. In combination, a plurality of parallel railway traffic routes each of which is provided with one or more switches and with a signal for governing traffic movements through the route, switch 20 locking apparatus for said routes comprising a stick relay for each of the parallel routes and

means controlled by given traffic conditions for energizing each of said stick relays if an associated signal indicates stop as well as means for retaining each of said stick relays in its energized condition independently of said given traffic conditions as long as an associated signal continues to indicate stop, group releasing apparatus for said switch locking apparatus comprising a manually controllable time releasing device as well as a plurality of locking release relays controlled by 10 the time releasing device and by back contacts of corresponding said stick relays and also means controlled by said locking release relays and by said time releasing device for energizing each of said stick relays upon the lapse of a given minimum period of time after an associated signal has been controlled to indicate stop, manually controllable apparatus controlled in part by said stick relays for operating said switches, and manually controllable means for clearing said signals. 15
